CONTACTOR

John B. Bubb, Palo Alto, and Charles E. Wallace,
San Jose, Calif.

Application January 12, 1946, Serial No. 640,789

1 Claim. (Cl. 191—35)

1 This invention relates to extended electrical conductors and current collecting shoes arranged to travel thereon for powering mobile equipment such as, for example, overhead cranes.

In general the objects of our invention include the provision of equipment of this type wherein an extended and insulated electrical conductor is formed of identical sections, any one of which can be readily removed and replaced without the necessity of first disconnecting and removing any other section; wherein an adequately insulated traveling contactor is maintained in positive and running electrical engagement with the extended conductor; and wherein the construction of these members is simple and relatively inexpensive.

The invention possesses other advantageous features, some of which with the foregoing will be set forth at length in the following description where that form of the invention which has been selected for illustration in the drawings accompanying and forming a part of the present specification is outlined in full. In said drawings, one form of the invention is shown, but it is to be understood that it is not limited to such form, since the invention as set forth in the claims may be embodied in a plurality of forms.

Referring to the drawings:

Fig. 1 is a longitudinal midsection of a sectionalized conductor and traveling contactor embodying our invention.

Fig. 2 is a vertical section taken on the section line 2—2 of Fig. 1 through one of the conductor joints.

Fig. 3 is a vertical section taken on the section line 3—3 of Fig. 1 through the traveling contactor.

Fig. 4 is an exploded view of one of the conductor joints.

Fig. 5 is a horizontal section taken on the section line 5—5 of Fig. 1 through one of the conductor joints.

As shown in these various figures, the extended conductor includes a plurality of identical conductor bars 11, rectangular in cross-section and conveniently made in ten-foot lengths. Formed on each end of each of the bars 11 is a notch 12, by which a flush lap joint can be made between each bar and the next succeeding bar, screws 13 being used to secure the overlapping ends. Fitted about each conductor bar is a sheet metal liner or inner sheath 14 provided on its lower side with an open slot 15 defined by laterally spaced downwardly extending flanges 16 and 17. Surrounding the liner 14 is an insulating sheath

18 of rubber or other insulating material provided on its lower side with a channel 19 for the accommodation of the flanges 16 and 17, the channels 15 and 19 being in open communication with the lower face of the conductor bar 11. Encasing the insulating sheath 18 is a one-piece metal outer sheath or casing 21 formed on its upper face with a central and upwardly extending folded rib 22, and at its lower end with inwardly turned flanges 23 and 24 underlying the base of the insulating sheath 18. The upper face of the outer sheath 21 forms roller trackways 25 and 26, the function of which will be presently described.

15 The liners 14 are of particular importance for they protect the insulating sheaths 18 from wear, and since they have a lower coefficient of friction than rubber, the bars 11 can be threaded through them more readily than through an unlined insulating sheath. Furthermore the use of the liners 14 permits the insulating sheaths 18 to be made of a relatively cheap grade of rubber.

Each end of the inner sheaths 14, insulating sheaths 18 and outer sheaths 21 terminates short 25 of the end of its associated conductor bar 11. As shown in Figs. 4 and 5, the sheath 14 terminates at a point 27, the insulating sheath 18 being provided at this point with a beveled end 28. The outer sheath 21 terminates at a point 29 immediately to the rear of the end 28.

30 As a result of this construction, the jointed ends of the conductor bars 11 are exposed, making each joint readily accessible in the event that any particular conductor bar 11 has to be repaired or replaced.

35 The joints thus exposed are insulated by removable sections including a pair of identical and opposed inner metal sheath sections 31 and 32 provided on their lower surface with downwardly extending flanges 33 and 34. The sections 31 and 32 and their downwardly extending flanges 33 and 34 are arranged to form a continuation of the inner metal sheath 14. Surrounding the opposed sheath sections 31 and 32 is an insulating sheath 35 having beveled ends 36 arranged to overlap the beveled ends 28 of the insulating sheath 18. Fitted over the sides of the insulating sheath 35 are a pair of opposed outer sheath members 37 and 38, each provided respectively with central upstanding ribs 39 and 41 and at 45 their lower edges with inwardly extending flanges 42 and 43. The upstanding ribs 39 and 41 are formed at each end with offset portions 44 and 50 45 arranged to overlap the adjacent ends of the ribs 22 of the outer sheaths 21. Each of the

offset portions 44 and 45 are fastened to the upstanding ribs 22 of the adjoining outer sheaths 21 by rivets 46. It will therefore be seen that the sheath sections encasing the conductor bars 11 can be readily removed to expose the flush lap joints formed on the end of the bars, and that any two adjacent conductor bars can be readily unjointed by simply unscrewing the screws 13. It should also be noted that the shoulders 47 and 48 of the outer sheath sections 37 and 38 form a continuation of the roller trackways 25 and 26. Riveted at spaced points along and to the upstanding ribs 22 are brackets 49 by which the structure so far described can be fastened to any suitable support.

Supported on each of the trackways 25 and 26 is a carriage 50 including a pair of longitudinally spaced rollers 51 and 52, each roller being journaled on a pin 53. Suspended from each of the pins 53 is a strap 54, a spacing washer being interposed between each strap and its associated roller. Supported by the straps 54 is a contact carrier 55 provided with upstanding lateral walls 56 and with upstanding end walls 57. Welded to each of the end walls 57 are a pair of transversely extending sleeves 58, and extending through each of the sleeves 58 is a bolt 59 by which the contact carrier 55 is fastened to the depending straps 54. Seated within the contact carrier 55 is a brush holder receptacle 61 made of plastic or other insulating material, the bottom wall of which is provided with a central opening 62. Accommodated within the receptacle 61 is a metal brush holder 63 formed with a plurality of longitudinally aligned, vertical compartments 64. Slideably disposed within each of the compartments 64 is a collecting brush 65, each of these brushes being urged upwardly by a spring 66 disposed in the lower end of each of the compartments 64 so that the upper end of each brush will be maintained in positive engagement with the conductor bar 11. Formed integral with the brush holder 63 is a button 70 extending downwardly through the opening 62 and which is insulated from the housing 55 by an insulating washer 67. Fastened to the button 70 by a screw 68 is the terminal loop 69 of a pigtail 71, the loop being insulated from the housing 55 by a washer 72. The hot leg of the circuit used for powering the mobile tool passes through the extended conductor bar 11, through the brushes 65, and through the pigtail 71.

Removably fastened to and across each pair of straps 54 by screws 73 is a longitudinally ex-

tending bar 74 and secured to the inner face of each of these bars between each pair of straps 54 is a shoe 75. The shoes 75 are arranged for sliding contact with the side walls of the outer sheath 21 and are preferably made of a self lubricated bearing metal. By resorting to this construction the rollers 52 can be maintained in proper alignment without the necessity of using rails and flanged rollers.

It will be seen that by resorting to a device of this character the conductor bars and the movable contactors are always adequately insulated, always in positive electrical contact with each other, and if need be any section of the extended conductor bar can be readily removed and a new one spliced in without disturbing any other section.

We claim:

A contactor comprising a casing having an elongated opening in one side and formed to provide an elongated trackway on the other side, electrical insulating material disposed within said casing and having walls defining an elongated channel including a centrally enlarged chamber merging with an outwardly opening narrow groove, a conductor bar within and substantially occupying said chamber, a conducting sheath having an enlarged portion interposed between said conductor bar and said walls in said chamber and having a narrow portion leaving an exposed portion of said conductor and lining the walls in said groove, a carriage movable on said trackway, and a narrow brush on said carriage extending into said channel between the confines of the narrow portion of said sheath to abut the exposed portion of said conductor.
